(57) **CLAIM**

The ornamental design for a universal door banner, as shown and described.

DESCRIPTION

The present application relates to commonly assigned U.S. patent application Ser. No. 29/468,518 filed Sep. 20, 2013, entitled Door Banner.

FIG. 1 is a top front left perspective view of the universal door banner.

FIG. 2 is a top, right and rear perspective view of the universal door banner.

FIG. 3 is a top view of the universal door banner.

FIG. 4 is a view of one side of the universal door banner.

FIG. 5 is a front view of the universal door banner.

FIG. 6 is view of the opposite side of the universal door banner.

FIG. 7 is a bottom view of a universal door banner.

FIG. 8 is a rear view of the universal door banner; and,

FIG. 9 is a top, right and rear perspective detail view of area 9 circumscribed within FIG. 2.

The present application is for the ornamental design of a flexible universal door banner that wraps around a typical door as shown in the attached figures. While not part of the design, the banner generally includes a logo or image positioned on the face of the door.

The broken line outlines of text and the areas within these broken lines on the front surface of the design depict features of the universal door banner that form no part of the claimed design. All other broken lines represent environmental structure that forms no part of the claimed design. The dot-dash-dot broken line circumscribing the area of the detail in FIGS. 2 and 9 forms no part of the claimed design.
